UNITED STATES PATENT OFFICE.

SCHUYLER C. LORD, OF EAST SURRY, MAINE.

CALENDAR ATTACHMENT FOR PENCILS AND PEN-HOLDERS.

SPECIFICATION forming part of Letters Patent No. 307,207, dated October 28, 1884.

Application filed July 23, 1884. (No model.)

To all whom it may concern:

Be it known that I, SCHUYLER C. LORD, of 5
East Surry, county of Hancock, Maine, have
invented a new and Improved Calendar At-
tachment for Pencils and Pen-Holders, of
which the following is a full, clear, and exact
description.

My invention consists in a tube provided
with a rotating sleeve, the whole being made
10 for fitting on the end of a pencil or a pen-
holder for use as a calendar, as hereinafter de-
scribed and claimed.

Reference is to be had to the accompanying
drawings, forming part of this specification, in
15 which similar letters of reference indicate cor-
responding parts in all the figures.

Figure 1 is a side view of the attachment
as applied to a pencil. Fig. 2 is a side view
of the parts as separated, and Fig. 3 is a
20 longitudinal section of the attachment as made
to hold a pen.

a is a tube, of suitable length, having a slot,
b, at one end, so that the tube can be readily
slipped on the end of a pencil or pen-holder,
25 and will be held by friction.

c is a shorter tube, fitted as a sleeve on the
tube *a* at one end thereof, and taking against
a shoulder, *d*. At the outer end of tube *a*
30 is a spring-tongue, *e*, cut out of the metal of
the tube, and having a lug or projection, *f*,
that engages any one of holes *g* in tube *c*,
whereby the latter is kept from rotating and
held in place.

The names of the days of the week are

placed on tube *a* in proper order around it, 35
and on tube *c*, in lines to correspond, are the
days of the month properly arranged, so that
the sleeve *c* can be set for any month. There
are seven of the holes *g*, whereby the lug *f*
40 holds the sleeve in place as set. To change
the adjustment, lug *f* is pressed down and the
sleeve turned.

h is a plug of rubber screwed into the end
of tube *a*, for use as an eraser. It serves also
45 to force the tongue *e* outward and prevent ac-
cidental disconnection of the lug. This rub-
ber plug is first removed when the calendar
is to be shifted.

This attachment is simple and useful, and
it may be formed to hold a pen, as in Fig. 3, 50
or applied to an ordinary pen-holder.

When made to hold a pen, the screw-thread
at the end serves to retain the wooden portion
of the holder or a lead-pencil, as indicated at *p*.

Having thus described my invention, I claim 55
as new and desire to secure by Letters Patent—

1. The calendar attachment consisting of
tube *a*, rotating sleeve *c*, and the spring-tongue
e, engaging the sleeve, combined for use sub-
stantially as described.

2. The combination, with tube *a*, sleeve *c*,
and tongue *e*, of the rubber plug *h*, as and for
the purpose specified.

SCHUYLER C. LORD.
